UNITED STATES PATENT OFFICE.

HERVEY W. FOWLER, OF CHICAGO, ILLINOIS.

ROLL FOR REDUCING OLD RAILS TO HOMOGENEOUS BARS.

SPECIFICATION forming part of Letters Patent No. 315,269, dated April 7, 1885.

Application filed June 7, 1883. (No model.)

To all whom it may concern:

Be it known that I, HERVEY W. FOWLER, of Chicago, in the county of Cook and State of Illinois, have invented certain new and useful 5 Improvements in Mechanism for Converting Railway T-Rails into Homogeneous Billets; and, I do hereby declare that the following specification, taken in connection with the drawings furnished and forming a part of the 10 same, is a clear, true, and complete description of my invention.

The prime object of my invention is to convert old rails into homogeneous "billets"—i. e., without flaw or seam—and germane thereto 15 another important object is to produce such billets in less time and with less labor than has, as I believe, been heretofore involved in their production. Another important object is to produce from such rails a homogeneous 20 billet, which in sectional area is only so far less than the aggregate sectional area of the head, web, and foot or flange of the rail, as is naturally incident to such necessary compression as will insure the condensation of the several 25 portions of the rail and the welding thereof into a homogeneous or seamless mass, so that, for instance, a billet substantially rectangular in cross-section and nearly square, developed from a given length of old rail of 30 average condition as to wear, would be, for instance, about one-fifth greater in length than the length of rail, thus enabling said billet to be more widely utilized in subsequent manufacture than if it were an ordinary flat 35 billet, or one substantially square and of lesser sectional area. Another important object is to produce a homogeneous billet from such rails with a minimum expenditure of or loss in heat, so that the billet may be directly and 40 immediately worked without additional heating into such forms as should involve the use of homogeneous or flawless metal—as, for instance, merchant bar-iron, bolts, and rail-spikes—and as an illustration of the value of 45 this latter feature I will state that I am enabled, by using spike-making machinery heretofore patented by me and the necessary preparatory rolls for working upon the billets, to convert a twenty-inch length of old rail into 50 rail-spikes within about twenty seconds after the rail has been properly heated for forming the billet. Heretofore old rail at a welding-

heat has been subjected to separate passes and operations for progressively turning the edges of the flange or foot toward the web preliminary to the ultimate consolidation thereof with the web and head; but I have discovered that said consolidation of the head, web, and flange can be thoroughly performed simultaneously at a single operation upon the rail, 60 and for the accomplishment of the ends hereinbefore recited, and such others as are obviously incident thereto, I subject the old rail to a welding-heat, as heretofore, and then for the first time, as I believe, I simultaneously 65 lap the flange on each side against the web and consolidate the head, web, and flange into welding contact. This consolidation is effected by pressure applied, mainly, at right angles to the plane of the web, supplemented by such 70 lateral or equivalent pressure as will cause the thin metal at the foot or flange to be folded against the sides of the web toward the head, and simultaneously merged with the metal in the web and head into a homogeneous mass. 75 I accomplish these ends by the use of a pair of rolls devised by me, whereby the head, web, and flange of a properly-heated rail are simultaneously consolidated in one "pass," so that the conversion of a convenient length of rail 80 into a homogeneous billet practically rectangular in cross-section and nearly square is performed instantaneously, the rolls for getting the best results being of unusually large diameter as compared with ordinary mill- 85 rolls, and operated at high speed. So far as my knowledge extends pairs of rolls as heretofore organized for converting old rails into billets have contained "box-passes" or coincident grooves, and I deem such rolls practically unsuited for obtaining the best results, because the metal should be at a welding-heat, and it therefore could not be well confined as against lateral displacement between the rolls adjacent to the pass. I employ a tongue-and- 90 groove pass in my rolls, the groove being preferably in the lower roll and the tongue on the upper roll. Such rolls, broadly considered, are not new; but I have no knowledge of any prior rolls of that general class which would 95 be suited for my purpose, although there are, no doubt, many rolls which could be employed with fair results, if modified or changed so as to embody certain features in construction 100

and arrangement which I have found to be important. My grooved roll is the first of which I have knowledge suited for heavy iron-rolling service, in which the periphery of the 5 roll at each side of the groove serves as an initial seat or bed for the metal which is to be rolled, and upon which said metal is subjected to change in form immediately preparatory to its actual occupation of the groove or pass. 10 My grooved roll is also the first suited for my purpose of which I have knowledge, wherein the entrance or mouth of the groove, by being slightly flaring or rounded, enables each side to serve as a "wiping-edge" for causing metal 15 supported upon the seat or bed at the periphery of the roll to be progressively turned at right angles and thence carried into the groove. My groove is necessarily sufficiently wider at its top than at its bottom to afford a 20 free clearance of the billet therefrom, and this inclination of its sides with the rounded or flaring entrance to said groove affords a lateral pressure upon the metal supplementary to the direct vertical pressure applied by the 25 tongue of the co-operating roll in the plane of the web of the rail.

In service my rolls involve what I believe to be a novel mode of operation in that the rail, *per se*, does not enter the pass, but it is 30 first worked by the peripheries of the tongue and the grooved roll wholly out of its normal form and forced into the groove flange foremost before the pass is actually reached, so that within the pass the welding consolidation and the incident elongation or drawing 35 of the metal are performed; but it is to be understood that although said radical change in the form of the rail occurs progressively immediately before the metal thereof actually 40 reaches the pass, the transformation of a piece of rail into a welded or homogeneous billet is performed by me almost instantaneously. I also employ for the first time, so far as I know, annular guides on the periphery of the grooved 45 roll at proper distances on each side of the groove, so that their edgewise contact with a rail assures an accurate location of the web of the rail with relation to the center of the groove, and locates the flange equally on each 50 side of said groove. I also employ a novel guide-box with my rolls, which is the first, so far as I know, which, while permitting the rear end of a rail to freely move in the plane of its web during a pass, separately confines 55 the head and the flange to said movement, thus assuring the delivery of the rail to the rolls in a predetermined position best conducive to the results desired.

To more particularly describe my invention, 60 I will refer to the accompanying drawings, in which Figure 1 is a front view of a pair of rolls as devised by me with my guide-box attached. Fig. 2 is a vertical central section of the same on line *x*. Fig. 3 is an enlarged sectional view of the coincident or working portions of the rolls as if engaging a piece of rail and converting it into a billet. Fig. 4 is an

end and a side view of a piece of T-rail as prepared for working. Fig. 5 is an end and a side view of a trimmed billet as preferably produced by me drawn upon a scale corresponding with that of Fig. 4, and fairly illustrating the comparative increase in length which I find to be most desirable, and also the preferred sectional form and comparative sectional area. Fig. 6 is an enlarged view of the rolls at the pass. Fig. 7 is an end view of the guide-box with rail therein.

The rolls A and B are mounted in heavy 70 housings, and have the usual adjusting or temper screws. The bed-roll A is provided with a groove, *a*, which may be varied in its general form without departure from my invention. Its sides should, however, be inclined, so that the top of the groove will be sufficiently wider than the bottom to afford free 85 clearance of the billet. For enabling the flange or foot of a rail to be readily "wiped" into the groove, it is desirable that the entrance thereto be flared as at *a'*; but a slightly- 90 rounded edge will serve a good purpose. As to dimensions, said groove may also be varied without departure from my invention; but I deem it preferable that it should be about equal in width to the width or lateral thickness 95 of the head of the rail to be worked; and I deem it advisable that it should never be narrower than the aggregate of the thickness of the web and the average thickness of the foot, because the web with the flange lapped 100 against the web on each side should be entered therein with comparative freedom. The depth of the groove may be varied according to the desired sectional form of the billet; but in working ordinary old rail into billets 105 for most purposes I prefer that the pass portion of said groove should in depth be so proportioned to its width that below the pitch-line and at the pass said groove will be nearly or substantially square in cross-section, as indicated in the drawings, it being understood 110 that said pitch-line is preferably located at about one-third the depth of the groove below the periphery of the roll. I obtain good results with my groove below the pitch-line so 115 proportioned in sectional area to the aggregate sectional area of the head, web, and foot 120 of the rail to be worked that a billet resulting from a piece of rail of a given length will be about one-fifth longer than the rail, the consolidation or compression incident to such a draw being sufficient as a rule to unite all 125 portions of the rail into welding contact. The periphery of the bed-roll at *b* serves as a seat for the flange of a rail on each side of the groove, and as it is important for the best 130 results that the web of the rail be located centrally over the groove and the foot or flange located equally on each side thereof, I employ edge guides *c*, which may be integral with the roll; but for purposes of adjustment they are constructed in the form of rings, and are provided with set-screws so that they can be 135 freely moved longitudinally on the periphery

of the roll toward or from the groove and thereafter firmly secured in position. The top roll, B, is provided with a tongue, *d*, which registers with and enters the groove of the 5 lower roll to the pitch-line, which, as before stated, is preferably located by me at about one-third of the depth of said groove. The working-face of the tongue *d* is flat; but for enabling it to readily bite upon or engage with 10 the end of a piece of rail it is roughened on its periphery by being provided at frequent intervals with slightly-projecting transverse bars or lugs *d'*; or, in lieu thereof, the tongue may be laterally scored at similar intervals. 15 If the lugs or bars be used, the tongue, after it has been properly turned off, may be transversely slotted in dovetail form, the lugs having bases correspondingly formed, thus enabling them to be readily replaced when 20 broken or worn.

I am aware that rolls having box-passes have heretofore been provided with studs or pins projecting into the pass, for enabling the rolls to more readily engage with a rail-head. 25 These rolls vary in their peripheral dimensions, the bed-roll being as much larger than the top roll as, say, one-third the depth of the groove *a*, at which point, as before stated, I prefer the pitch-line to be located, so that the 30 diametrical dimensions of the rolls, measuring from the pitch-line, shall be substantially equal; but inasmuch as the metal in the rail is wholly changed in form before it reaches the pass, it is obvious that the rolls must at least be of such diameter as to afford between 35 the periphery of the tongue and the seat of the bed-roll a good gripping-bite upon the end of a rail in its normal form when presented with its web in a vertical position, with the flange 40 bearing on the seat *b*, and the head engaged by the periphery of the tongue. In practice I deem it desirable that said rolls should be at least thirty inches in diameter, although I have used them considerably smaller, and am 45 aware that they can be of greater dimensions without materially affecting the results. Having reference to the power involved in the work, I prefer, however, to have my rolls only so large in diameter as will assure a prompt 50 and effective grip of a full-sized rail or rail-end presented with its flange bearing on the periphery of the grooved roll.

As thus far described, it will be understood that a rail at welding-heat is presented to the 55 rolls with its flange bearing upon the seat and guided, as described, until engaged at its head by the periphery of the tongue, which, as the rail is drawn inward, forces said rail flange foremost into the groove, and simultaneously 60 laps the flange against the web and forces the head, flange, and web into welding contact, and that at the pass proper the metal is heavily compressed and drawn.

For enabling the prompt and reliable delivery of a rail to the rolls, I have devised the 65 guide-box C, which contains a head-guide and

a flange-guide, and is sufficiently deeper than the height of a rail to permit the latter to rise and fall freely while its web is maintained in a vertical position. The head-guide portion 70 of the box is much deeper than the thickness of a rail-head, and only slightly greater in width than the width of said head, and the flange-guide portion is a little wider than the width of a rail-flange, but considerably deeper 75 than the thickness of said flange.

Guide-boxes have heretofore contained a head-guide and a flange-guide for use in combination with grooved rolls, affording a box-pass; but in said prior guide-boxes the rail is 80 confined against vertical as well as against lateral movements.

It will be seen that with my rolls the rail must be easily and accurately guided longitudinally to the seat on the bed-roll, and that 85 when its head is engaged by the tongue of the upper roll the front end is forced at once downward flange foremost into the groove, and that as the rail advances its rear end must be free to rise and fall without material 90 deviation from its vertical position, although I find that with my rolls as constructed and operated by me, I obtain homogeneous billets, regardless of the twisting by the rail, or its variation in position, so long as it can be 95 made in any way to enter the groove and reach the pass at which the maximum compression is applied. Said guide-box has a nose, as at *e*, which projects well forward and between the rolls, and is so shaped as to closely approach the sides of the tongue and overlie the foot or flange guides on the lower roll. In cross-section its upper portion or head-guide *f* is but little wider than the head of a rail, and its lower portion or flange-guide *g* 100 is but little wider than the foot or flange of a rail, and its interior height is sufficiently greater than the height of the rail to allow of its rise and fall, which in extent seldom exceeds the depth of the groove in the bed-roll, 105 and therefore the flange-guide has vertical dimensions slightly greater than the depth of the groove, and the head-guide is of sufficient height to normally accommodate the head of the rail, and also during its vertical movement. 110

Although for producing homogeneous billets, the rolls, as shown with a single pass, may be wholly relied upon, it is obvious that such a tongue-and-groove pass may be embodied in large rolls otherwise constructed for various lines of rolling, whereby the billets may be directly converted into bars or rods of various sectional form and areas. 115

Having thus described my invention, I claim 120 as new and desire to secure by Letters Patent—

1. The combination of a tongue-roll, having lugs or bars on its tongue-face, and a grooved roll provided with a seat on each side of its groove for supporting the flange of a railway-rail, and thereby co-operating with the tongue-roll in enabling the tongue of the latter to 130

force said rail flange foremost into the groove, substantially as described.

2. The combination of a tongue-roll and a roll having a groove and a seat on each side of said groove, and a rail-flange guide for each seat, substantially as described, whereby a rail bearing upon said seat is accurately located with its web centrally over the groove and the head of the rail located for proper engagement by the tongue.

3. The combination, with the grooved roll having a rail-flange seat on each side of the groove, of adjustable annular rail-flange guides for each seat, substantially as described.

15 4. The combination of the rail-reducing tongue-and-grooverolls and a guide box which

is considerably deeper than the height of a rail, has a head-guide much deeper than the thickness of a rail-head and but little wider than said head, and a flange or foot guide but little wider than a rail-flange, but much deeper than the thickness of said flange, substantially as described, whereby a rail passing through said box to the rolls can at its rear end freely rise and fall while the web of the rail is maintained in a vertical position, as set forth.

HERVEY W. FOWLER.
